PROCESS OF TREATING OIL

Gustav A. Beiswenger, Elizabeth, N. J., assignor
to Standard Oil Development Company, a cor-
poration of Delaware

Application January 21, 1930, Serial No. 422,255

4 Claims. (CL 196—79)

This invention relates to a process of treating oils and more particularly to an advantageous combination of distillation and treating steps. In a way, the present invention may be considered as an improvement over the process disclosed in U. S. Patent application Serial No. 408,966 of A. A. Wells, filed November 22, 1929. According to the process of the last mentioned application lubricating oils are taken off as side streams, or as bottoms from the distillation equipment, and are submitted while hot to treatment with decolorizing agent such as finely divided clay (acid treated clay—fuller's earth). Finished lubricating oils are thus obtained without acid treatment.

The invention will be fully understood from the following description read in conjunction with the drawing, the single figure of which is a diagrammatic elevation of an apparatus adapted to carry out the invention.

In pipe still operation the feed stock to be treated is passed through a series of heated tubes into a fractionating tower in which the distillation takes place, and products are separated according to their boiling point. It is customary to steam strip the various side streams and the bottom stream, or at least some of these streams, to free them from the light ends. The strippers consist, in principle, of small bubble towers with bell cap plates or an equivalent construction. The stream to be stripped is introduced into the stripper above the uppermost plate and leaves the stripper at the bottom thereof after having come in contact with superheated steam passed in countercurrent with the oil stream. The light products in the steam are then returned to the fractionating tower. The stripped products may be of poorer color than desired hence require clay contacting or some other means of decolorization. If the normal procedure of clay contacting is resorted to after the oil has been cooled and removed from the equipment, a considerable fuel and equipment cost is encountered, due to the necessity of re-heating the oil to relatively high treating temperature.

In my improved method the contacting is carried out in the same stripper utilizing equipment and heat already available. It is only necessary to provide an opening in the steam stripper for the introduction of clay either as obtained, or in the form of a slurry mixed with some oil of the same character as the stream treated. The agitation necessary for the treatment is effected by the steam passing countercurrent to the oil

stream for the purpose of stripping the same. It will be understood that the treating temperature in my process is predetermined by the temperature of the oil stream passed through the stripper and, therefore, the regulation of the 60 degree of treating must be carried out principally by a careful control of the treating time. The latter may be carried out by increasing or decreasing the amount of liquid retained on the bell cap plates, and by regulating the amount of 65 liquid held in the bottom portion of the stripper. The method of this regulation will be obvious to those skilled in the art and will, therefore, not be described in more detail. Another obvious method of regulating the treating time consists 70 of introducing the slurry of oil and solid treating agent into the stripping column at such a height thereof that the solid treating agent stays in contact with the oil just for the amount of time required for treating.

In the figure, 1 denotes the feed line; 2 the heater; 3 the fractionating tower; 4 the cooler for the overhead products; 5 a reflex line; 6 and 6' the strippers, two of which are shown by way of illustration; on these strippers 7 and 7' are 80 the lines for taking off the stream from the fractionating tower 3; 8 and 8' are lines for introducing steam; line 9 and 9' are the lines for introducing the slurry of clay and oil; 10 and 10' are the return lines for the steam and stripped vapors; 11 and 11' the lines for removing the mixture of stripped oil and clay from the stripper; 12 and 12' are filters for the separation of 85 the oil from the clay.

In carrying out the process the charge, such 90 as reduced crude, is fed by means of a pump through the feed line to a heater in which it passes through a series of tubes heated by the combustion gases of the furnace. The oil is heated here to the required temperature and then 95 discharged into the fractionating tower which may contain bell cap plates, or equivalent fractionating means. The charge is separated here into several fractions such as, for example, gas oil fraction obtained as overhead product, paraffin distillate, and a cylinder stock fraction obtained as side streams, and a bottoms consisting of asphalt. The distillation and fractionation 100 may be carried out under any pressure such as, for example, under atmospheric pressure or under vacuum. The side stream such as the paraffin distillate and a cylinder stock shown in the drawing are treated with a slurry of clay and paraffin oil and cylinder stock respectively, while these streams pass through the strippers 6 and 110

6'. The mixture of treated oil and clay leaves through the bottom lines 11 and 11', passes through coolers 13 and 13' through the filters 12 and 12' and through coolers 14 and 14' to the storage tanks (not shown).

5 The following example will serve to illustrate my process:

10 A 50% reduced Mid-Continent crude oil was submitted to distillation under vacuum in the pipe still described above. The products obtained were: asphalt, cylinder oil and paraffin distillate. The cylinder oil was treated with 2 lbs./gal. of Filtral in the stripper allowing a time of contact of about 1 minute. The temperature in the cylinder oil stripper was: 625° F. at the top and 575° F. at the bottom. The cylinder oil which had a viscosity of 133 sec. Saybolt Universal at 210° F. was diluted for the color determination in the following proportions: 15 parts of oil with 85 parts of 21 color (on the Saybolt apparatus) water white kerosene. The color of an untreated sample of cylinder oil (dilute) was $\frac{3}{4}$ on the Tagliabue-Robinson colorimeter while that of the clay treated oil was $1\frac{3}{4}$.

20 It will be understood that my process can be applied not only with pipe still distillation units but also with the strippers of fractionating towers attached to shell stills.

25 Having thus described my invention and the method of carrying it out what I claim is the following:

30 1. The process of treating oil which comprises passing the oil stock through a distillation and fractionating zone, taking off vapors from the distillation and fractionating zone, withdrawing a liquid stream of the reflux oil intermediate of the lightest and heaviest fractions in the fractionating zone, and passing the withdrawn

stream through a stripping zone in contact with a solid treating agent.

35 2. The process of treating oil comprising passing the oil stock through a distillation and fractionating zone, withdrawing liquid stream of the reflux oil intermediate of the lightest and heaviest fractions in the fractionating zone introducing the liquid stream obtained in the fractionating zone into a stripping zone, introducing a slurry of solid treating agent and oil into the stripping zone in contact with the liquid stream, passing steam through the stripping zone in countercurrent to the liquid stream, returning a mixture of steam and vapors into the fractionating zone, removing the liquid stream together with the solid treating agent from the stripping zone and separating the solid treating agent from the liquid stream.

40 3. The process according to claim 2 in which a liquid stream is introduced into the top portion of the stripping zone and the slurry of finely divided clay and oil is introduced into the stripping zone at such a height thereof that the finely divided clay stays in contact with the liquid stream while passing through the stripping zone, the time of contact being controlled by the amount of liquid held in the bottom portion of the stripping zone.

45 4. The process of treating oil which comprises passing the oil stock through a distillation and fractionating zone, taking off vapors from the distillation and fractionating zone, withdrawing a plurality of liquid streams of oil from regions of different temperature in said zone, and passing the withdrawn streams through a corresponding plurality of stripping zones in which the individual oil streams are separately and individually contacted with solid treating agent.

GUSTAV A. BEISWENGER.
